UNITED STATES PATENT OFFICE

JAMES C. HAMILTON, OF ARLINGTON, MASSACHUSETTS, ASSIGNOR OF ONE-HALF TO
WILLIAM H. HASTINGS, OF MALDEN, MASSACHUSETTS

ARTICLE HOLDER

Application filed June 29, 1927. Serial No. 202,430.

This invention relates to an article holder and more particularly to a case for cigarettes and other similar articles.

While my invention may be variously modified and applied for use with a number of articles, I have for the purposes of illustration described it herein as applied to a cigarette case.

The aim of this invention is to provide a convenient case or holder of simple construction which may be manufactured and sold at a comparatively low price.

A further object of this invention is to provide a cigarette case adapted to be kept in the pocket and from which a cigarette may be withdrawn by the use of one hand only, thereby making it especially useful in situations where the user has only one hand free as in driving a vehicle.

20 In carrying out my invention I form a holder having two or more folds in substantially parallel planes. My device may be made from a single blank of sheet metal or other stiffly resilient material which in the 25 prepared embodiment of my invention is bent upon itself in opposite directions forming a central wall, and two outer spring clips or covers. The cigarettes may be introduced into the device at opposite ends by 30 slipping them under the free ends of the spring clips and between the latter and the central wall, and are retained by the resilient pressure of the clips, being prevented from sliding out sidewise by flanges provided 35 upon the sides of the clips or other means provided therefor. The spring clips are formed with slots extending to their free edges through which the finger may be introduced to withdraw the cigarette lying 40 nearest the free edge.

The invention will best be understood if the following description is read in connection with the accompanying drawings in which,

45 Fig. 1 is a perspective view of one embodiment of my invention showing the manner in which the clips or covers of my device may be slotted to give access to the cigarettes.

50 Fig. 2 is an end view of the embodiment illustrated in Fig. 1 showing the manner in

which the metal blank is bent in forming the case, and flanged to prevent lateral movement of the cigarettes contained therein.

Fig. 3 is a view of the metal blank or stamping before it is folded to form the case. 55

Fig. 4 is a side view of the embodiment of Fig. 2 showing the flanged edge of the covers or clips welded together.

Fig. 5 is a perspective view of the case having a modified form of slot adapted to 60 receive a follower.

Fig. 6 is a side view of a modified form of case having its surface ribbed.

Fig. 7 is a side view of another modified embodiment of my invention. 65

Fig. 8 is a detail view on the line 8—8 of Fig. 5 showing a follower mounted in the longitudinal slot in the face of the case.

Fig. 9 is a detail view on line 9—9 of Fig. 6. 70

Fig. 10 is a perspective view of another embodiment of my invention having a modified form of side flange.

Fig. 11 is a top view of the blank from which the case shown in Fig. 10 is formed. 75

Figs. 12 and 13 are top and side views respectively of the modification shown in Fig. 10 embodying my invention.

The holder which is the subject of my invention may be formed from a blank cut out 80 of a sheet of suitable material such as metal, celluloid, hard rubber or the like, by a single stamping operation. This blank as shown in Fig. 3 comprises a central portion 20, and the end portions 21 and 22 which form the 85 clips or covers of the case. Each of the end portions 21 and 22 is slotted centrally as shown at 23 and 24, and is provided with the flanges 25. The end portions 21 and 22 of the blank are bent along the lines $x-x$ and 90 $y-y$ respectively, in reverse manner forming a plurality of substantially parallel walls. The free edges of the end portions 21 and 22 are curved somewhat inwardly to retain the cigarettes within the holder and 95 the side flanges 25 are turned inwardly to prevent displacement of the cigarettes laterally. When the end portions of the blank are properly turned the case will at all times retain its shape, the covers or clips being suf- 100

sufficiently resilient to permit the case to be filled with cigarettes, and to exert an inward pressure sufficient to retain them in place. While it is not necessary it may be found desirable to increase the solidarity of the case by welding the edges 25 together as shown at 30 of Fig. 4.

In Figs. 5 and 8 the case is shown provided with a narrow slot 31 in which the follower 10 32 may be slidably mounted for aiding in discharging the cigarettes. If desirable the faces of the folds of the case may be ribbed as shown in Figs. 6 and 9, to prevent lateral movement of the cigarettes within the 15 holder.

In Fig. 7 a modified form of folder is shown, having the end portion bent in the same direction separated by a central wall 33 of double thickness. The end folds or clips 20 may be provided with flanges as described in connection with Fig. 3, or if desired the flanges stamped in any suitable design such as is shown at 34 for example, may be provided.

25 In Figs. 10 to 13 a further modification of my invention is shown in which the side flanges 25 shown in Figs. 1 to 4 are replaced by the side walls 40. These side walls may be of sufficient width when bent over to reach 30 across the sides of the case and may be soldered or otherwise joined to opposite exterior folds or clips of the case, thereby increasing the solidarity of the holder and increasing the rigidity of the outer folds. The 35 outer faces of this modification of my invention are slotted as described above, and may if desired be provided with a follower such as is shown in Fig. 5.

A particular advantage of my invention is 40 the provision of the slot in the end or clip portion of the holder, since it permits the user to withdraw the cigarettes with one hand, and without removing the case from the user's pocket or other position in which it 45 is carried.

Many modifications of my device may be made without departing from my invention which is to be limited only by the following claims.

50 What I claim is:

1. An article holder comprising an integral blank of any suitable material bent upon itself in opposite directions, forming a central wall and two outer self-supporting 55 covers, said covers provided with central longitudinal slots open at the free end of said covers.

2. An article holder comprising an integral blank of a stiffly resilient material having 60 a plurality of substantially parallel walls, said walls provided with longitudinal slots having openings reversely disposed to each other and separated by a central wall member located within said holder.

65 3. An article holder having a central wall

portion separating a plurality of substantially parallel side portions, each of said side portions being slotted, said slots being open at one end thereof.

4. An article holder comprising a unitary 70 member having a central wall and two outer walls, said outer walls having oppositely extending free ends with slots extending inwardly from said free ends.

5. A holder comprising a unitary member 75 bent to form a central wall joining two oppositely extending walls, each having a free end and a slot extending inwardly therefrom.

6. A holder comprising a unitary member 80 bent to form a plurality of substantially parallel clips separated by a central wall portion, each of said clips being slotted.

7. In an improved cigarette case, the combination of a central wall, a side wall 85 located on either side of said central wall, a finger slot located in each of said side walls and adapted to receive the finger of the operator for the purpose of expelling cigarettes thereby.

8. A cigarette case formed from a single blank having a central portion, and slotted end portions, the said central portion adapted to form a common back between the 90 said slotted end portions and separate such end portions thereby.

9. A cigarette case formed from a unitary blank and bent in a reverse manner providing several substantially parallel portions, the outer of said portions being provided with lateral flanges having free edges to allow for transverse movement of said parallel portions, said portions further provided with longitudinally disposed slots, said slots being open at one end thereof.

10. An article case having at least three substantially parallel walls comprising a unitary member, the outer walls of said case being slotted, said slots being open at one 105 end thereof.

11. In a cigarette case, a plurality of clips formed from a unitary member, each of said clips provided with a solid back portion and a slotted front portion, one end of said slots being open to allow for the withdrawal 115 of one or more cigarettes by the finger of the operator.

12. In a cigarette case, a plurality of clips formed from a thin sheet material, each of said clips provided with a front and back portion one of said portions being provided with an open ended slot for the purpose of withdrawing cigarettes therein exposed.

In testimony whereof I affix my signature.

JAMES C. HAMILTON.
